METALLIC WALL TILING

Filed Feb. 1, 1926

Fig. 2.

Fig. 1.

George L. Bennett INVENTOR

Frank J. Wentworth BY ATTORNEY.

UNITED STATES PATENT OFFICE.

GEORGE L. BENNETT, OF CLEVELAND, OHIO.

METALLIC WALL TILING.

Application filed February 1, 1926. Serial No. 85,108.

My invention relates to metallic wall tiling, and more particularly to the construction of such tiling and the manner of mounting different sections of same in relation to 5 each other and to the wall of a building.

The wall tiling of my invention, is made of sheet metal, one surface of which is so formed and finished as to resemble ceramic tiles. The construction is such, that large sheets of 10 this material may be secured in relation to the wall of a building and to adjacent sheets, in a manner to avoid the presence of perceptible joints or crevices at the parting between adjacent sheets while avoiding the necessity 15 for the use of nails or fasteners passing through the metallic sheets with the heads exposed.

It is also essential to secure the tiling sheets in position by concealed means which 20 will not only facilitate the mounting of the tiling upon a wall, but will afford reinforcement to the material of the sheets when positioned upon the wall, and impart a desirable rigidity to the whole tiling structure.

25 In conjunction with tiling sheets of the character above referred to, I provide base strips secured in relation to the flooring of a room and co-operating with the lower edges of the sheets of tiling, and also cap pieces 30 secured to the studding and co-operating with the top edge of the tiling sheets.

By a construction of tiling embodying my 35 invention, each tiling sheet receives both longitudinal and vertical support from the studding or walls of the building, and the various sheets are united in a manner to permit the edges of adjacent sheets to be brought into close abutting relation with each other when tiling is being installed, the 40 supporting means permitting the free movement of the various sheets in relation to each other in fitting them in position.

The invention consists primarily in metallic wall tiling embodying therein a metallic 45 sheet having one face thereof suitably decorated, and horizontally extending, co-operating, interlocking members adapted to be connected with the studding of the wall of a building, and connected with the undecorated 50 rated face of said sheet, respectively; and in such other novel features of construction and combination of parts as are hereinafter set forth and described, and more particularly pointed out in the claims hereto appended.

55 Referring to the drawings,

Fig. 1 is a front view of a fragmentary portion of a metallic wall tiling installation embodying the invention, with portions thereof broken away;

Fig. 2 is a vertical section on the line 60 2-2 of Fig 1; and

Fig 3 is a horizontal section on the line 65 3-3 of Fig. 1.

Like letters refer to like parts throughout the several views.

In the embodiment of the invention shown in the drawings, *a* indicates the studding of the room of a building to which the tiling of my invention is to be attached, *b* the flooring of the room, and *c*, the dado or wall of 70 the room above the tiling. It will readily be understood, however, that the tiling, instead of serving merely as a sort of wainscoting, may be extended to the ceiling of the room, and may even constitute the ceiling. 75

The tiling of my invention is formed of thin sheet metal, preferably ranging from .03 to .06 of an inch, and is in sheet form of a length corresponding with the height of the tiling which is desired, and of a width which 80 may be conveniently handled. In the accompanying drawings, portions of three such sheets, *d*, *e* and *f* are shown. With metal of the thickness of that used in tiling, it is essential to afford support or reinforcement therefor at closely adjacent points, not only to avoid waves due to buckling in the wall finish, but to permit the edges of adjacent sheets or 85 sections to be brought and maintained in close abutting relation. The use of nails in 90 securing sheets of metal tiling in position is not desirable, because the exposed heads of such nails is a serious defacement to the wall, and irregularity in the spacing of the studs makes it impracticable to secure a proper fitting of the edges of adjoining sections with 95 relation to each other.

To permit the tiling to be positioned with relation to the wall, and adjoining sheets thereof in relation to each other, while at the same time imparting that rigidity to the whole tiling structure which will cause it to always present a smooth finish, and avoid the presence of any appreciable crack or crevice at the parting between adjoining sections or 100 sheets, I provide concealed co-operating interlocking means upon the undecorated face or back of each sheet and adapted to be firmly secured to the studding of the building structure. Such means will afford a plurality of 105 110

points of supports and re-enforcement to each sheet, both vertically and laterally thereof, thus not only firmly securing each tile sheet in position in relation to the studding, but in 5 relation to adjoining sheets, while at the same time affording very effective stiffening means for the tiling sheets.

The interlocking means above referred to, in the embodiment of the invention shown, in- 10 cludes light metal, Z-shaped furring strips *g* adapted to be nailed or otherwise secured to the studs *a* or walls of the building. These furring strips extend horizontally for sub- 15 stantially the full length of the wall to which the tiling is to be applied, and a plurality of such furring strips, spaced vertically at pre- determined distances are used. The lower flange of the Z is used in securing said fur- ring strips to the studding.

20 Co-operating with the furring strips *g* is a plurality of Z strips *h* corresponding in number and in their spacing with the strips *g*, the Z strips *h* having one flange thereof, that extending upwardly, secured in any de- 25 sired manner as by spot, or other, welding or soldering methods to the undecorated, or rear, face of each sheet. The dimensions of the fur- ring strips *g* are such as to secure the desired spacing of the tiling sheet from the furring 30 strips, while the dimensions of the co-oper- ating interlocking members or Z strips *h* are such as to afford, as to each strip, a down- 35 wardly presented socket with which the up- wardly presented flange of the strips *g* is adapted to have a close sliding fit.

The strips *h* preferably extend for the full width of the tiling sheet, or from side edge to side edge thereof, thus affording both vertical and horizontal support for the tiling 40 sheet. In this manner the sheet is supported both vertically and horizontally at a plurality of adjacent points, and the load of the sheet is so distributed as to relieve each of the co- 45 operating interlocking members from any material stresses which might result in buck- 50 ling of the tiling sheet.

The form of the interlocking members is such as to permit vertical or horizontal move- 55 ment of the sheet when mounting it upon a wall, this construction being highly desirable as facilitating not only the mounting of the sheet, but the bringing of one edge of each sheet as it is being mounted, into the desired close abutting relation to the sheet previously mounted. The furring strips *g* and the co- 60 operating strips *h* carried by the tiling sheets may be made of fairly light metal stock, per- mitting sufficient resiliency in the strips *h* to secure the desired tightness of the sheet with relation to the furring strips and with the 65 wall, and to add greatly to fire resistance of such tiling.

To prevent movement of one tiling sheet with relation to the adjacent tiling sheet intermediate the points of support afforded by the

interlocking strips *g* and *h*, I provide the side edges of each sheet with members adapted to interlock with co-operating members ad- jacent the edge of the adjoining sheet which will ensure accuracy in the aligning of the 70 edges of these sheets as they are mounted in relation to each other, and will prevent any through or unsealed opening from room to back of furring. These devices also serve to stiffen the tiling sheets at the edges thereof 75 intermediate the strips *h*, and thus impart rigidity to the tiling adjacent said edges.

The interlocking members, in the embodiment of the invention shown, consist of a plate *i* secured by spot, or other, welding methods to the undecorated or rear surface of one tiling sheet, this plate being offset along the edge thereof adjacent the edge of the tiling to form a channel open at the top and at the bottom adapted to receive a flat plate *j* secured by spot, or other, welding methods adjacent the edge of the adjoining tiling sheet, the plate *j* projecting beyond the edge of the sheet carrying same so as to lap the parting between the adjoining sheets and enter the channel formed by the plate *i* in en- gaging relation to the offset portion of this plate, and with the portion of the sheet adja- cent the edge thereof.

For the purpose of standardizing the til- 95 ing sheets, I preferably provide one edge thereof with a plate *i* and the other edge thereof with a plate *j*, although this arrange- 100 ment obviously is not essential so long as one of the metal sheets has a plurality of plates intermediate the strips *h* thereon and the ad- joining tiling sheet has co-operating plates *j*. The plates *i* and *j* are of a height to oc- 105 cupy sufficient space between the strips *h* to impart the desired rigidity to the tiling sheets at the edges thereof intermediate said plates. The plates *i* are offset to an extent to ensure a tight sliding fit between the substantially parallel offset portion and the tiling sheet and the projecting portion of the plate *j*.

In conjunction with the tiling sheets, I provide base and cap strips adapted to co- 110 operate respectively with the upper and lower edges of each tiling sheet.

The base strip comprises a section *k* which may be in the form of a cove, and is adapted to be secured to the flooring adjacent the studding *a*. Secured thereto by spot, or other, welding methods, is a fitting *m* having parallel flanges *m'*—*m*² offset in relation to each other, the flange *m'* being sufficiently deep to afford ample space for the welding operation, this flange being of a depth to en- gage and be secured to the base *k* below the upper edge thereof so as to form an upwardly presented pocket. The lower edge of each tiling sheet has secured upon the undecorated or rear face thereof, a flat plate *n* adapted to enter the pocket above referred to, and with the decorated face of the tiling sheet in sub- 125 130

stantial alinement with the upper adjoining portion of the base strip. The fitting *m* and plate *n* in conjunction with the base strip *k*, impart rigidity to the lower edge of each 5 tiling sheet. The outer face of the base strip *k* is suitably decorated to harmonize with the decorations of the tiling sheets.

The top of each sheet is secured in position by means of a cap strip so formed as to give 10 the desired finish to the tiling, this cap being secured to the studding and having an interlocking relation with the upper edge of each tiling sheet. This cap strip is indicated at *o* in the drawings, and has, at the lower edge 15 thereof, a plate *p* secured thereto and projecting from said lower edge, this plate being secured to said cap strip by spot, or other, welding methods. The projecting edge of the plate *p* enters a socket or channel 20 formed by an offset plate *q* secured adjacent the upper edge of the tiling sheet by spot, or other, welding methods, it being preferable to have the strip *q* formed integrally with the uppermost strip *h* in the interest of economy 25 in the production of the tiling sheet. The cap strip is provided with a flat flange *o'* through which nails may be driven into the studs in securing this cap strip in position with relation to the building structure and 30 the various tiling sheets.

By this construction the uppermost strip *g* may be utilized for imparting rigidity both adjacent the upper edge of the sheet and adjacent the lower edge of the cap strip. The 35 configuration of the base strip *k*, and the cap strip *o* may vary in order to secure the desired finish or decorative effect at the bottom and at the top of the tiling. The outer face of the cap strip is suitably decorated to harmonize 40 with the tiling sheets. The flange *o'* and the nails securing same to the studding may be concealed either by the wall finish above the tiling, in the event that a wainscoting effect is secured, or by the cornice or cove at 45 the ceiling, or by the metal plates of the ceiling in the event that a metal ceiling is used.

The various binder strips *h* are secured to the various tiling sheets during the process of 50 the manufacture of these sheets, and the base strip *k* and cap strip *o* are also finished in their entirety at the shop. In this manner uniformity or standardization of the tiling sheets is secured.

55 The various tiling sheets are of a width to permit their convenient handling both in the construction of the sheets and in assembling them upon a wall. The various strips *g*—*k*—*o* however, may be made of any desired 60 length, since, by reason of the light construction of these parts, they may be cut to the proper size when mounting them upon the studding, and the manner of assembling the tiling requires no particular length of same.

65 In applying tiling embodying the inven-

tion, the base strips *h* are first secured in position to the studding near the floor *b* of a room, it being preferable to secure the strips adjacent the lower edge thereof to the flooring, as by means of nails. By curving the 70 strips *h* as shown, a base cove is provided.

When the strips *h* are in position the tiling sheet is brought in relation to the studding with the various strips *h* positioned above the furring strips *g*, and the lower edge of the 75 sheet in a position above the strip *h* where as the sheet is permitted to descend, the plate *n* adjacent and projecting beyond the lower edge of the sheet, will enter the socket formed by the fitting *m*, and the various plates *h* 80 upon the strip, will respectively pass behind and engage the upwardly presented flange of the several furring strips *g*.

Before thus positioning the tiling sheet, the various furring strips are secured to the 85 studding as by nailing, it being possible to accurately locate and space these strips because of the known distance between the strips *h* upon the tiling sheet, and the known height 90 of the base strip *k*. As the strips *g* are positioned it is merely necessary to see that they are parallel with the floor line, the strips being run for substantially the full length, or width, of a room and being substantially 95 continuous.

When one sheet has been positioned as described, the next sheet is handled in like manner receiving, however, as it is being lowered lateral movement sufficient to cause the plates *i* and *j* upon the edge of adjoining plates to 100 interlock in the manner above described, thus not only ensuring a tight closing of the parting between these sheets and sections, but an accurate alinement of the sheets upon opposite sides of the parting and a stiffening of 105 both sheets adjacent the parting. The continuity of the furring strips *g* and the open channel formed by the plates *j* permit the necessary vertical and lateral sliding movement of the tiling sheets.

110 If the dimensions of a room are such that a part, section or sheet is necessary to finish a wall, the workman may remove sufficient from the one edge of any sheet to secure a sheet of the desired width for the proper 115 fit. The various strips *h* being of light weight may be cut by means of a special tool such as is used with metallic electrical moulding. Mitre or fitting cuts, at the ends of the base and cap strips may be made in the same way for fitting at corners or about door or window trims.

120 After the various tiling sheets are thus positioned, the cap strips *o* are positioned in relation to the upper edge of the different sheets coming within the length of such a strip, being brought with the plate *p* carried thereby in engageable relation with the offset plate *q* adjacent the upper edge of each of the tiling 125 sheets and secured in relation to same. The 130

wall or ceiling finish above these cap strips will conceal the means for securing the strips to the studding and the floor finish may be made to conceal the means for attaching the base strips in relation thereto.

In a completed wall, each tiling sheet will be supported vertically at a plurality of parallel levels, thus relieving the furring strips from any substantial load which would 10 tend to cause them to sag between the studding. Furthermore, what load is placed upon these furring strips will be distributed throughout the entire width of the sheet. This arrangement prevents vertical buckling 15 of the sheets, holds them firmly with relation to the studding, ensures their being perfectly flat, and secures a stiffening action in part by the offset flanges, or Z-shape, of the strips *h* and in part by the engagement of the material of the sheet with the vertically extending flange of the furring strips *g* with which the strips *h* co-operate.

The co-operating interlocking means formed by the plates *i* and *j* serve merely as 25 alining members and reinforcing members, since when the sheets are once assembled, there will be no tendency for them to separate at the parting, particularly as the strips *h* will impart rigidity to the sheet, which will 30 prevent the formation of vertical buckles or waves.

Throughout the structure all means of securing the tiling sheets in position are or may be concealed, and the manner of securing the 35 sheets in position is such as to avoid any likelihood of the marring or defacement of the decorative face of the sheet by the workman in securing the sheets in position.

Spot, or other, welding methods are used 40 to avoid the presence upon the exposed face of each sheet of tilting of securing means which upon the decorative face will amount to a defacement. Whether the strips *h* and *g* are secured to the sheet, or the fittings *m* and 45 strips *n* are secured to the base and cap strips respectively, before or after the decoration of the sheet, is a matter of convenience of handling the materials in the course of manufacture.

50 The number and spacing of strips *h* and furring strips *g* is dependent upon the desired quality of the finished tiling. By placing these strips closely together, greater rigidity is secured, but installation becomes more 55 expensive because of the increased labor of production and of installation.

The tiling may be quickly and accurately assembled upon a wall, thus permitting a low cost of installation by low priced labor. The 60 dimensions of the various furring strips may be such as to secure the desired spacing of the sheets such as *d*, *e* or *f* with relation to the studding or with regard to other parts of the wall finish. If, as in the drawings, a lath 65 and plaster dado is used, the tiling sheets will

be positioned more remote from the studs than where the tiling goes from floor to ceiling.

The entire tiling structure is made of fairly light sheet metal stock, which is permissible 70 by reason of the numerous points of interlocking reinforcing and supporting devices imparting rigidity to the finished surface.

It is not my intention to limit the invention to the precise details of construction shown 75 in the drawings, it being apparent that such may be varied without departing from the spirit and scope of the invention.

Having described the invention, what I claim as new and desire to have protected by 80 Letters Patent, is:—

1. Metallic wall tiling embodying therein a metallic sheet having one face thereof suitably decorated, and a plurality of co-operating, interlocking supported members adapted 85 to be connected in horizontally extending, parallel spaced relation to each other, to the studding of the wall of a building, and connected with the undecorated face of said sheet in a similar horizontally extending, parallel spaced relation to each other intermediate the top and bottom edges of said sheet, respectively, whereby no portion of the supporting means for said tiling is exposed. 90

2. Metallic wall tiling embodying therein 95 a metallic sheet having one face thereof suitably decorated, a plurality of co-operating, interlocking supported members adapted to be connected with the studding of the wall of a building, and connected in horizontally 100 extending, parallel spaced relation to each other, to the undecorated face of said sheet in a similar horizontally extending, parallel spaced relation to each other intermediate the top and bottom edges of said sheet, respectively, and vertically extending co-operating interlocking members at the edges of adjacent sheets connected with said sheets within the edges of the undecorated face thereof, and positioned between said horizontally extending members whereby adjoining sheets are alined one with the other and are reinforced adjacent the parting between said sheets whereby no portion of the supporting and alining means for said tiling is exposed. 110

3. Metallic wall tiling embodying therein a metallic sheet having one face thereof suitably decorated, horizontally extending, co-operating, interlocking members adapted to be connected with the studding of the wall 120 of a building, and connected with the undecorated face of said sheet, respectively, a metallic base strip adapted to be connected to the studding of the walls of a building, and co-operating, interlocking members connected respectively to the undecorated face of said sheet and with said base strip. 125

4. Metallic wall tiling embodying therein a metallic sheet having one face thereof suitably decorated, horizontally extending, co- 130

- operating, interlocking members adapted to be connected with the studding of the wall of a building, and connected with the undecorated face of said sheet, respectively, 5 vertically extending co-operating interlocking members at the edges of adjacent sheets and positioned between said horizontally extending members whereby adjoining sheets are alined one with the other and are reinforced adjacent the parting between said sheets, a metallic base strip adapted to be connected to the studding of the walls of a building, and co-operating interlocking members connected respectively to the undecorated face of said sheet and with said base strip.
6. Metallic wall tiling embodying therein a metallic sheet having one face thereof suitably decorated, horizontally extending, co-operating, interlocking members adapted to be connected with the studding of the wall of a building, and connected with the undecorated face of said sheet, respectively, a cap strip adapted to be connected with the studding of the wall of a building, and co-operating interlocking members connected respectively with the undecorated face of said sheet and of said cap strip.
7. Metallic wall tiling embodying therein a metallic sheet having one face thereof suitably decorated, horizontally extending, co-operating, interlocking members adapted to be connected with the studding of the wall of a building, and connected with the undecorated face of said sheet, respectively, vertically extending co-operating interlocking members at the edges of adjacent sheets and positioned between said horizontally extending members whereby adjoining sheets are alined one with the other and are reinforced adjacent the parting between said sheets, a cap strip adapted to be connected with the studding of the wall of a building, and co-operating interlocking members connected respectively with the undecorated face of said sheet and of said cap strip.
8. Metallic wall tiling embodying therein a metallic sheet having one face thereof suitably decorated, horizontally extending, co-operating, interlocking members adapted to be connected with the studding of the wall of a building, and connected with the undecorated face of said sheet, respectively, a cap strip adapted to be connected with the studding of the wall of a building, and co-operating interlocking members connected respectively with the undecorated face of said sheet and of said cap strip.
9. Metallic wall tiling embodying therein a metallic sheet having one face thereof suitably decorated, a plurality of horizontally extending, substantially Z-shaped furring strips adapted to have one flange thereof secured to the studding of the wall of a building, and the other flange thereof presented upwardly, a plurality of horizontally extending, substantially Z-shaped strips each having one flange thereof secured to the undecorated face of said sheet, and the other flange thereof extended downwardly in co-operating interlocking relation with the upwardly extending flange of the furring strip, a plate secured to said sheet adjacent one edge thereof, said plate being offset in relation to the sheet to form a channel open at the top and at the bottom, and a flat plate secured adjacent the edge of an adjoining tiling sheet, projecting beyond said edge and adapted to enter the channel of the plate on the adjacent sheet.
10. Metallic wall tiling embodying therein a metallic sheet having one face thereof suitably decorated, horizontally extending, co-operating, interlocking members adapted to be connected with the studding of the wall of a building, and connected with the undecorated face of said sheet, respectively, a metallic base strip comprising a section adapted to be secured to the flooring, a fitting having parallel flanges offset in relation to each other, one of said flanges being secured to said strip adjacent the upper edge thereof, and the other being adapted to be secured to the studding of the building, and a plate secured to, and projecting beyond, the lower edge of said metallic sheet adapted to enter the space between the flange of said fitting secured to the studding and the portion of said base strip parallel therewith.
11. Metallic wall tiling embodying therein a metallic sheet having one face thereof suitably decorated, horizontally extending, co-operating, interlocking members adapted to be connected with the studding of the wall of a building, and connected with the undecorated face of said sheet, respectively, a cap strip, a flange upon said strip whereby the strip may be secured to the studding, a plate secured to, and projecting beyond, the lower edge of said strip, and an offset plate secured adjacent the top of said tiling sheet forming a socket adapted to receive said plate.
12. Metallic wall tiling embodying therein

a metallic sheet having one face thereof suitably decorated, a plurality of horizontally extending, substantially Z-shaped furring strips adapted to have one flange thereof secured to the studding of the wall of a building, and the other flange thereof presented upwardly, a plurality of horizontally extending, substantially Z-shaped strips each having one flange thereof secured to the undecorated face of said sheet, and the other flange thereof extended downwardly in co-operating interlocking relation with the upwardly extending flange of the furring strip, a plate secured to said sheet adjacent one edge thereof, said plate being offset in relation to the sheet to form a channel open at the top and at the bottom, a flat plate secured adjacent the edge of an adjoining tiling sheet, projecting beyond said edge and adapted to enter the channel of the plate on the adjacent sheet, a metallic base strip comprising a section

adapted to be secured to the flooring, a fitting having parallel flanges offset in relation to each other, one of said flanges being secured to said strip adjacent the upper edge thereof, and the other being adapted to be secured to the studding of the building, a plate secured to, and projecting beyond, the lower edge of said metallic sheet adapted to enter the space between the flange of said fitting secured to the studding and the portion of said base strip parallel therewith, a flange upon said strip whereby the strip may be secured to the studding, a plate secured to, and projecting beyond, the lower edge of said strip, and an offset plate secured adjacent the top of said tiling sheet forming a socket adapted to receive said plate.

In witness whereof I have hereunto affixed my signature this 23rd day of January, 1926.

GEORGE L. BENNETT.
